UNITED STATES PATENT OFFICE

LOUIS H. SHOEMAKER, OF PITTSBURGH, PENNSYLVANIA

OPERATING MECHANISM FOR LIFT-BRIDGES.

1,210,715.

Specification of Letters Patent.

Patented Jan. 2, 1917.

Application filed March 9, 1916. Serial No. 83,078.

To all whom it may concern:

Be it known that I, LOUIS H. SHOEMAKER, a citizen of the United States, and resident of Pittsburgh, in the county of Allegheny and State of Pennsylvania, have invented certain new and useful Improvements in Operating Mechanisms for Lift-Bridges, of which the following is a specification.

My invention relates to the construction of operating mechanisms used in actuating bridges employed in spanning canals and small streams and similar locations, and of the class having a lifting span adapted to be raised vertically above the level of the water to a height enabling the lifting span to clear passing vessels and to be lowered into position for traffic to pass over the bridge from one to the other of the approaches at the ends of the bridge.

One object of this invention is to provide a lift bridge of improved construction and having novel means whereby the vertically moving lifting span of the bridge is raised to a height sufficient to clear vessels passing under the bridge and is positively lowered into position enabling traffic to pass over the bridge from one to the other of the approaches at the ends of the bridge.

Another object of my invention is to provide a bridge lifting mechanism having a novel arrangement of lifting cables whereby the opposite ends of the lifting span of the bridge are connected to a cable operating mechanism located in proximity to one end of the bridge.

Another object of the invention is to provide a lift bridge having cable towers at the ends thereof and having improved means for leading the cables to the cable operating mechanism adjacent to one end of the bridge.

A further object of the invention is to provide a lift bridge having improved means for counterbalancing the lifting span of the bridge and for equalizing the tension on the cables connecting the counter-balance weights and lifting span of the bridge.

A further object of the invention is to provide novel means for connecting the bridge and lifting mechanism therefor whereby the bridge is positively actuated in the bridge lowering operation.

A still further object of the invention consists in the provision of bridge lifting mechanism having improved means whereby the lifting span of the bridge is maintained in a horizontal plane in the raising and lowering

operations and by which the tension on the cables forming part of the bridge lifting and lowering mechanism is equalized.

Still further objects of the invention consist in the provision of the novel combinations and arrangements of parts illustrated in the drawings, specifically pointed out in the appended claims, and more fully described hereinafter.

Referring now to the drawings forming part of this specification, Figure 1 is a diagrammatic side elevation showing a bridge having approaches and towers at the ends of the bridge arranged in accordance with my invention. Fig. 2 is a diagrammatic side elevation showing the arrangement of the bridge operating cables and sheave wheels therefor at the left hand end of the bridge structure shown in Fig. 1. Fig. 3 is a diagrammatic side elevation showing the arrangement of the bridge operating cables and cable sheaves at the right hand end of the bridge structure shown in Fig. 1. Fig. 4 is an end elevation showing the tower at the right hand end of the bridge structure of Fig. 1, with the bridge operating cables and sheaves thereon as arranged in accordance with my invention. Fig. 5 is an end elevation similar to that of Fig. 3, showing the tower at the left hand end of the bridge structure of Fig. 1, and having the operating cables and sheaves thereon as arranged in accordance with this invention. Fig. 6 is a detail plan showing the relative arrangement of sheave wheels on the top of the towers for the cables connecting the ends of the bridge and counter-balance weights. Fig. 7 is a detail side elevation showing the equalizing apparatus whereby the lifting cables are connected to the counter-balance weight and the tension on the cables is equalized. Fig. 8 is a sectional plan showing a preferred arrangement of winding drums and drum operating mechanism by which the lifting span is positively raised and lowered in the operation of the lift bridge. Fig. 9 is a sectional side elevation of the operating mechanism shown in Fig. 8. Fig. 10 is a detail side elevation showing the arrangement of sheave wheels at the base of the towers by which the direction of travel of the cables is guided and changed.

In the accompanying drawings, the numeral 2 designates the lifting span of the bridge, which is positioned between towers 3 and 4, and which is arranged to be raised

and lowered from the position shown by full lines into and out of the position shown dotted in Fig. 1. The towers as shown are framed into and form part of approaches 5 and 6 leading to the ends of the lifting span when the lifting span is in lowered position (the position shown in full lines in Fig. 1). The lifting span 2 comprises two built up trusses each having a top chord 7 and bottom chord 8 which are connected by vertical struts 9 and diagonal bracing 10 riveted at their ends to the top and bottom chords of the structure in the usual known manner. Extending between the two trusses and supported by the bottom chord 8 is a series of transverse floor beams α α and longitudinal beams 11^a, and on top of the floor beams is a floor 12 made of wood as shown.

Each of the bridge approaches 5 and 6, of which there is one at each end of the bridge, comprises two built up trusses, each truss having a top chord 13, bottom chord 14, vertical struts 15, and diagonal bracing 16, and the wooden floor 17 for the approaches is carried on longitudinal floor beams 18^a and transverse floor beams α α between the trusses, the transverse beams being supported at their ends by the bottom chords 14.

The towers 3 and 4, of which there is one at each end of the bridge, are formed of pairs of columns 19 and 20 which are connected together by horizontal struts 21 and diagonal or cross bracing 22. The lower ends of the tower columns 19, 20, are framed into the ends of the trusses forming the approaches to the lifting bridge span 2, and the columns 19, 19, and 20, 20, forming each tower are connected in pairs at their upper ends by lattice girders 19^a, 20^a:

The construction of the lifting span of the bridge and approaches being known and not forming part of this invention, is not further described.

Adjustably secured by means of a turnbuckle 24 to each corner of the left hand end of the lifting span 2 of the bridge, is a bridge lifting cable 25, these cables extending upwardly and after passing over one of the lifting cable-sheaves 26 at the top of the tower and engaging with a guiding sheave 27, extend downwardly and pass under sheaves 28 rotatably mounted on the bottom chords 14 of the lifting span 2 of the bridge. (See Figs. 2 and 5). The cables 25 then extend across the bridge and after passing under one of the sheaves 29 at the other or right hand end of the lifting span 2 extend upwardly and over the pairs of sheaves 30 and 31 on the top of the tower 4, then downwardly under one of the sheaves 32 on the bottom chords 14 of the approach 4 and around the sheave 34, and are connected one to the under side of the drum 38 and one to the upper side of the drum 39 forming part of the cable actuating mecha-

nism, which is located beneath the approach 6 at the right hand end of the bridge. Also secured by means of a turnbuckle 24 to each corner of the lifting span 2 at the left hand end of the bridge, is a lowering cable 35. The cables 35 extend downwardly, pass around sheaves 36 on the lower end of the columns 19 of the tower 3, and then extend upwardly and pass around one of the sheaves 28 mounted on the bottom chord 8 of the lifting span 2, and, after extending across the bridge, one cable at each side thereof, the cables 35 pass over sheaves 29, downwardly under sheaves 37 on the lower end of the columns 19 of the tower 4, then upwardly and around sheaves 32 on the bottom chord 14 of the approach 6, then extend to and around one of the sheaves 34, being connected, one cable to each of the winding drums 38 and 39. (See Figs. 2, 5 and 8).

Secured one to each corner of the right hand end of the lifting span 2 by means of a turnbuckle 24 are lifting cables 41 for this end of the bridge, these cables extending upwardly and passing around one of the sheaves 30 on top of the tower 4 at the right hand end of the bridge structure shown in Fig. 1. The cables 41 then extend downwardly, pass around one of the sheaves 29 on the end of the lifting span 2 and then extend upwardly, and after passing over one of the pairs of sheaves 30 and 31 at the top of the tower, extend downwardly and around one of the sheaves 32, and from the sheaves 32 around a sheave 34, and are fastened one to the winding drum 38 and one to the drum 39 forming part of the cable operating mechanism. Also secured by means of a turnbuckle 24 to each corner of the lifting span 2 of the bridge at the right hand end thereof, are lowering cables 47 which extend downwardly, engage with a sheave 37, then extend upwardly and pass around one of the sheaves 29, then extend downwardly and pass around one of the sheaves 37, then pass around another of the sheaves 32 and around a sheave 34, and then extend one to each of the winding drums 38 and 39 of the cable operating mechanism to which the ends of the cables 47 are fastened.

Pivotedly connected to the framework of the towers 3 and 4 are counter-weighted, T-shaped levers 48 having a weight 48^a adjustably secured on one end thereof. The opposite end of the levers 48 has idler sheaves 49, 50, on the ends of the arm forming the head of the T-shaped levers, a pair of these sheaves 49, 50, engaging with each of the hoisting ropes 25, 41, and the counter-weight 48^a causing the sheaves to equalize the tension put upon the ropes. A similar counter-weight mechanism may be employed on the lowering ropes 35, 47, when found necessary or desirable.

Opposite the right hand end of the bridge, 130

beneath the floor and floor beams of the approach 6 for this end of the bridge are the winding drums 38 and 39, both of which are mounted on a shaft 51 mounted in suitable bearings 52, 53, and having a spur gear 5 wheel 54 on one end thereof. The spur 10 wheel 54 is connected by pairs of reducing gears 55, 56, 57, 58, 59 and 60, to a spur pinion 61 on the end of the armature shaft 62 of the electric motor 63 by which the bridge 15 raising and lowering cables are positively actuated in raising and lowering the bridge.

Rotatably mounted on top of and at the corner of each tower 3 and 4 is a set of one 15 or more sheave wheels 64 for the counter-balance ropes or cables 65 and 66, 67 and 68. Secured by the loops in the ends thereof to a pin or shaft 72 on the ends of the lifting span 2 of the bridge are the counter-weight 20 cables 65, 66, 67, 68, which are arranged in pairs, these cables extending upwardly and then downwardly around the sheave wheels 64 and the loop formed in each cable passing around a sheave wheel 69, the sheave 25 wheels 69 being pivotally connected by a lever 69^a to the yoke 70 fastened to each end of the counter-weight 71. The yoke 70 also has guiding sheave wheels 72 secured thereon to engage with one strand of the looped 30 ropes or cables 65, 66, 67, 68, so as to keep the vertically extending strands of the cables in parallel relation and the same distance apart as the distance between the centers of the grooves in the series of sheave wheels 64. 35 (See Fig. 7.)

The counter-weights 71, one at each end of the bridge, to which the yokes 70 are fastened, are conveniently arranged to extend across the width of the bridge at the end of 40 the approaches thereto when the lifting span 2 is in lifted position and form barriers to prevent pedestrians or traffic from accidentally stepping off the approaches when the lifting span of the bridge is in raised or 45 lifted position.

The operation of my improved apparatus will be readily understood. The motor 63 is caused to rotate in the required direction and actuate the lifting cables 25 and 41, 50 and the lifting span 2 of the bridge being balanced by the counterbalance weights 71 the power required in lifting is materially reduced. As the lifting span 2 is raised the counterweights 71 descend and bar the passage of traffic at the ends of the bridge approaches when the lifting span is in raised 55 position. When lowering the bridge span the lowering cables 35, 47, which are connected at one end to the lifting span 2 and 60 at the other to the winding drums, 38, 39, pull the lifting span 2 downwardly so that the bridge is positively actuated in lowering the lifting span.

The advantages of my invention will be 65 appreciated by those skilled in the art. The

apparatus is simple, and is readily kept in repair. By leading the lifting cables and lowering cables from one end of the bridge across the length of the bridge and by connecting these cables to a common operating mechanism, the lifting span of the bridge is maintained in horizontal position in the raising and lowering position. This arrangement of cables also avoids the necessity of providing girders or struts connecting the top of the tower at one end with the tower at the opposite end of the bridge to take the stresses or strains set up in the towers when the cables extend from the top of the tower at one end to the top of the tower at the opposite end of the bridge. By leading the cables from the remote end of the bridge across the lifting bridge span to the end of the bridge adjacent to the bridge lifting mechanism, the height of the towers necessary to use with a given clearance or head room is materially reduced.

Modifications in the construction and arrangement of the parts may be made without departing from my invention as defined in the appended claims.

I claim:—

1. In a lift bridge, the combination with a vertically moving lifting span, towers at the ends of said lifting span, and a cable operating mechanism adjacent to one end of the lifting span, of a series of sets of lifting cables whereby said span is raised, said lifting cables being secured at one end to said cable operating mechanism and extending upwardly and then downwardly over sheaves on the upper end of the bridge tower adjacent to said operating mechanism, one end of the cables in part of said sets of cables being adjustably secured to the adjacent end of the lifting span and part of said sets of cables leading across the lifting span and extending upwardly and then downwardly over sheaves on the upper end of the other of the two towers, and having one end thereof adjustably secured to the other end of the lifting span, and a series of sheaves rotatably mounted on the lifting span and the towers to guide and change the direction of travel of said sets of cables in raising and lowering the lifting span.

2. In a lift bridge, the combination with a vertically moving lifting span, towers at the ends of said lifting span, and a cable operating mechanism adjacent to one end of the lifting span, of a series of sets of lifting cables whereby said span is raised, a series of sets of lowering cables whereby said span is positively moved into lowered position, said lifting cables being secured at one end to said cable operating mechanism and extending upwardly and then downwardly over sheaves on the upper end of the bridge tower adjacent to said operating mechanism, one end of the cables in part

of said sets of cables being adjustably secured to the adjacent end of the lifting span and part of said sets of cables leading across the lifting span and extending upwardly 5 and then downwardly over sheaves on the upper end of the other of the two towers, said part of the sets of cables having one end thereof adjustably secured to the other end of the lifting span, and a series of 10 sheaves rotatably mounted on the lifting span and towers to guide and change the direction of travel of said sets of cables in raising and lowering the lifting span.

3. In a lift bridge, the combination with a vertically moving lifting span, towers at the ends of said lifting span, and a cable operating mechanism adjacent to one end of said lifting span, of a series of sets of cables whereby said lifting span is raised 15 and lowered, said cables being secured at one end to the cable operating mechanism and at least part thereof extending upwardly and then downwardly over rotatable sheaves on the upper end of the bridge 20 tower adjacent to said operating mechanism, one end of the cables in part of said sets of cables being secured to the adjacent end of the lifting bridge span with at least part of said sets of cables leading across the lifting 25 span and extending upwardly and then downwardly over sheaves on the upper end of the other of the two towers, said part of the sets of cables having one end thereof secured to the other end of the lifting span, and means on the lifting span and towers to guide and change the direction of travel of said sets of cables in raising and lowering 30 the lifting span.

35 4. In a lift bridge, the combination with a vertically moving lifting span, towers at the ends of said lifting span, and a cable operating mechanism adjacent to one end of said lifting span, of a series of sets of cables whereby said lifting span is raised and lowered, said cables being secured at one end to the cable operating mechanism and at least part thereof extending upwardly and then downwardly over rotatable sheaves on the upper end of the bridge 40 tower adjacent to said operating mechanism, one end of the cables in part of said sets of cables being secured to the adjacent end of the lifting bridge span with at least part of said sets of cables leading across the lifting span and extending upwardly and then downwardly over sheaves on the upper end of the other of the two towers, and having one end thereof secured to the other end of the lifting span, and means on the lifting span and towers to guide and change the direction of travel of said sets of cables in raising and lowering the lifting span.

45 5. In a lift bridge, the combination with a vertically moving lifting span, towers at the ends of said lifting span, and a cable operating mechanism adjacent to one end of the lifting span, of a series of sets of lifting cables whereby said span is raised, said lifting cables being secured at one end 50 to said cable operating mechanism and extending upwardly and then downwardly over sheaves on the upper end of the bridge tower adjacent to said operating mechanism, one end of the cables in part of said sets of cables being secured to the adjacent end of the lifting span and part of said sets of cables leading across the lifting span and extending upwardly and then downwardly over sheaves on the upper end of the other of the two towers, and having one end thereof secured to the other end of the lifting 55 span, and means on the lifting span and towers to guide and change the direction of travel of said sets of cables in raising and lowering the lifting span, and means on said tower arranged to engage with cables and equalize the tension on said cables.

60 6. In testimony whereof I have hereunto set my hand.

LOUIS H. SHOEMAKER.
